UNITED STATES PATENT OFFICE.

CLYDE L. WELSH, OF PITTSBURGH, PENNSYLVANIA.

PARACHUTE.

1,327,932.

Specification of Letters Patent. Patented Jan. 13, 1920.

Application filed April 17, 1919. Serial No. 290,855.

To all whom it may concern:

Be it known that I, CLYDE L. WELSH, citizen of the United States, residing at Pittsburgh, in the county of Allegheny and State 5 of Pennsylvania, have invented certain new and useful Improvements in Parachutes, of which the following is a specification.

This invention relates to improvements in parachutes and particularly to that type of 10 parachute adapted for being attached and carried upon the back of the aviator.

The primary objects of this invention are to provide a device of the character described, which may be worn by an aviator 15 without impeding his movements in the operation of the aeroplane, and which is positive in its operation by eliminating the danger of entanglement of the lines to which the case or dome of the parachute is attached.

Other objects of this invention are to provide a parachute of the type set forth which is simple in its construction and arrangement, strong, durable and efficient in its use 25 and inexpensive to manufacture.

To the accomplishment of these and such other objects as may hereinafter appear the invention consists of the novel construction, combination and arrangement of parts here- 30 specifically described and illustrated in the accompanying drawing, wherein is shown an embodiment of the invention.

In the drawing forming a portion of this specification and wherein like numerals of reference designate corresponding parts throughout the several views:

Figure 1 is a perspective view of my im- 35 proved parachute in the open or expanded position.

Fig. 2 is a cross sectional view of the hinged portion of the rim and brace.

Fig. 3 is a side elevational view of the device in its collapsed state as worn by the aviator during all flights.

It is a well known fact, corroborated by statistics, that most of the aviation casualties are due to the fall after the aeroplane has become inoperable from any reason whatsoever, and it is my intention to reduce 45 these casualties to a minimum by providing a compact parachute which is designed to be worn at all times, during a flight, upon the back of the aviator. It is only necessary for the aviator to leap clear of his aeroplane 55 when damaged or unmanageable, when the expansion of my improved parachute will

immediately check the rapidity of his descent.

Referring more in detail to the drawing, there is shown in Fig. 1, the case or dome 60 1, made preferably from canvas reinforced by a plurality of flexible members or lines 2 which are attached thereto in any suitable manner.

Centrally disposed and secured in the 65 dome 1, is the disk 3, of any suitable material, to which the flexible members or lines 2 converge and are attached.

The circular rim 4 carries a plurality of 70 spring reels 5 equally spaced thereon, each of which engages one of the flexible members 2. The rim 4 is pivotally connected, by means of the hinge 6, to the brace 7, which is shaped to conform to the contour of the body of the aviator. The heavy strap 8, 75 secured to the brace 7 and adapted to pass under the arms and be buckled across the breast of the aviator, is provided for attaching my improved parachute to the body of the aviator.

To palliate the inconvenience to the aviator using my improved device, the outer surface of the brace 7 is provided with the cushion 9.

For the purpose of holding the device in 85 its collapsed state upon the back of the aviator, I provide a flexible member or guy 10, one end of which is attached to the rim 4 at a point diametrically opposite the hinge 6, and the other end, passing through the 90 aperture 11 in the brace 7, is provided with the ring 12 adapted to engage in the hook 13 which is secured to the strap 8.

The spring 14, attached to the rim 4 and to the brace 7, is of sufficient strength to 95 force the rim 4 to a position almost at right angles with respect to the brace 7 when the guy 10 is released by removing the ring 12 from the hook 13.

In practice the operation of my device is 100 as follows: The parachute, in its collapsed state as shown in Fig. 3 of the drawing, is strapped upon the back of the aviator by means of the strap 8 which passes under his arms and is securely buckled over his 105 breast. The guy 10 passes between his legs and the ring 12 placed on the hook 13. The dome 1 will be held in its collapsed position by the tabs 15 which are clamped between the rim 4 and the brace 7. When desiring 110 to make a descent the aviator will leap clear of his aeroplane and remove the ring 12

from the hook 13, which will allow the spring 14 to force the rim 4 out at right angles or until the ring 12 on the guy 10 strikes the aperture 11 in the brace 7.

5 The tabs 15 now being released, the dome 1, now held only by the cords or wires 16 running crosswise in the rim 4, will be expanded by the currents of air against the under side thereof caused by the rapidity 10 of the descent. The reels 5 will let out their respective lines 2, which are of equal length, until all lines are drawn taut. With the parachute in this position the descent may be safely made. When it is desired to fold 15 the device the spring reels 5 will rewind the lines 2, and the dome 1 held in collapsed state as heretofore described. The guy line 10 acts as a substantial brace while making a descent and a plurality of them 20 may used if so desired.

From the foregoing description, taken in connection with the accompanying drawing, the advantages of the construction and the method of operation will be readily apparent to those skilled in the art to which the invention appertains, and while describing the principle of operation of the invention together with the device which is now considered to be the best embodiment there- 25 of it is to be understood that the device shown is merely illustrative and that various changes in the form, proportion and the minor details of construction may be resorted to without departing from the principle or sacrificing any of the advantages 30 of the invention as defined in the appended claims.

What I claim as new and desire to secure by Letters Patent is:

40 1. A parachute comprising a flexible dome, a rim, a plurality of reels mounted thereon, and flexible members connecting the said dome to the reels.

2. A parachute comprising a flexible dome, a rim, a plurality of reels mounted thereon, flexible members connecting the said dome to the reels and means for securing the said device to the body of an aviator.

45 3. A paracute comprising a flexible dome, a circular rim, flexible members connecting the said dome to the rim, and means for automatically releasing the said flexible members for expanding the dome, substantially as described.

50 55 4. A parachute comprising a flexible dome, a circular rim, flexible members connecting the dome to the rim, and means carried on the said rim permitting the release of the flexible members for the purpose 60 of expanding the said dome.

5. A parachute comprising a flexible dome, a circular rim carrying a plurality of reels, flexible members connecting the dome to the rim, and means hingedly connected

to the said rim for securing the device to the body of an aviator.

6. A parachute comprising a flexible dome, a circular rim, flexible members connecting the dome to the rim, and means for automatically withdrawing the flexible member 70 for the purpose of collapsing the said dome, substantially as described.

7. A parachute comprising a flexible dome, a circular rim, flexible members connecting the dome to the rim, and a plurality 75 of spring reels carried by the said rim for automatically withdrawing the said flexible members for collapsing the said dome, substantially as described and for the purpose set forth.

8. A parachute comprising a flexible dome, a circular rim, a plurality of reels mounted thereon, flexible members connecting the dome to the rim, and a brace hingedly connected to the rim for securing the 85 device to the body of an aviator.

9. A parachute comprising a flexible dome, a rim carrying a plurality of reels, flexible members connecting the dome to the rim, a brace hingedly attached to the rim, 90 and means for holding the said device in a collapsed position, substantially as described.

10. In a parachute the combination comprising a flexible dome, a rim having a plurality of reels mounted thereon, flexible members connecting the dome to the rim, a brace hingedly connected to the rim, and means for automatically positioning the 95 said rim at right angles with respect to the said brace for expanding the said dome, substantially as described and for the purpose set forth.

11. In a parachute the combination comprising a flexible dome, a rim having a plurality of reels mounted thereon, flexible members connecting the dome to the rim, a brace hingedly connected to the rim, and tabs attached to the dome adapted for being clamped between the rim and the brace for securing the device in a collapsed position, 105 substantially as described and for the purpose set forth.

12. In a parachute the combination comprising a flexible dome, a circular rim having a plurality of reels mounted thereon, flexible members connecting the dome to the rim, a brace hingedly connected to the rim, a spring for positioning the rim at right angles with respect to the brace and a guy 115 line for limiting the action of the said spring, substantially as described and set forth.

13. In a parachute the combination comprising a flexible dome, a circular rim, a plurality of spring reels mounted on the said rim, flexible members connecting the said dome with the rim, a cushioned brace hingedly connected to the rim, tabs attached to the dome adapted for being clamped between 125

the rim and the brace for holding the device in collapsed position, a spring for forcing the rim to a position at right angles with respect to the brace for expanding the device, straps attached to the brace for securing the device to the body of an aviator, and a guy line for limiting the action of the said spring and supporting the said brace, sub-

stantially as described and for the purpose set forth.

In testimony whereof I affix my signature in the presence of a witness.

CLYDE L. WELSH.

Witness:

JENNIE JONES.
